(57) **CLAIM**

The ornamental design for a protective sleeve nut, as shown and described.

DESCRIPTION

FIG. 1 is a top perspective view of one embodiment of a protective sleeve nut showing my new design.

FIG. 2 is a bottom perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof.

FIG. 8 is a bottom plan view thereof.

FIG. 9 is a sectional view thereof taken along section line 9-9 shown in FIG. 7; and,

FIG. 10 is another top perspective view thereof.

The pair of closely spaced jagged lines intersecting the drawings with the bracket on the side in FIGS. 1-6 and 9, depict indeterminate length.

The broken lines represent an environment of use and form no part of the claim. The broken away symbols indicate that any portion of the article beyond what is shown forms no part of the claimed design.
